United States Patent [19]
Rosner

[11] Patent Number: Des. 362,591
[45] Date of Patent: **Sep. 26, 1995

[54] KITCHEN TOOL HANDLE

D. 312,749 12/1990 Kessler D7/395
3,906,632 9/1975 Oppenheimer 30/322

[75] Inventor: Charles I. Rosner, Highland Park, Ill.

Primary Examiner—Terry A. Wallace

[73] Assignee: Ekco Housewares, Inc., Franklin Park, Ill.

Attorney, Agent, or Firm—Henry D. Pahl, Jr.

[**] Term: 14 Years

[57] CLAIM

The ornamental design of a kitchen tool handle, as shown and described.

DESCRIPTION

FIG. 1 is perspective view of a kitchen tool handle showing my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a left side elevation view thereof; and,

FIG. 7 is a right side elevation view thereof.

The broken lines showing the scraper are for illustrative purposes only and form no part of the claimed design.
